Tobacco Pouches By: Smokey Mountain found on Amazon (Jun. 17, 2023) https://www.amazon.com/Smokey-Mountain-Pouches-Nicotine-Free-Tobacco-Free/dp/B095V7X5WS/ref=sr_1_33?crid=HMDY7M8VGTBU&keywords=chewing+tobacco+pouches&qid= (May 25, 2021).*

Primary Examiner — Rebecca Tsehay(74) Attorney, Agent, or Firm — Rimon, P.C.; Dale L. Rieger(57) CLAIM

The ornamental design for a nicotine pouch as shown.

DESCRIPTION

FIG. 1 is a perspective view of the nicotine pouch.

FIG. 2 is a side view of the nicotine pouch.

FIG. 3 is another side view of the nicotine pouch.

FIG. 4 is a front view of the nicotine pouch.

FIG. 5 is a back view of the nicotine pouch.

FIG. 6 is a top view of the nicotine pouch; and,

FIG. 7 is a bottom view of the nicotine pouch.

The broken lines in the drawings depict portions of the nicotine pouch that form no part of the claimed design.

1 Claim, 7 Drawing Sheets(56)
